(57) **CLAIM**

The ornamental design for a soap holder, as shown and described.

DESCRIPTION

FIG. 1 is a right side view of my invention design for a soap holder illustrated in an intended orientation and its environment;

FIG. 2 is a front perspective view for a soap holder according to my new inventive design;

FIG. 3 is a front view thereof;

FIG. 4 is a right side view thereof;

FIG. 5 is a rear view thereof;

FIG. 6 is a bottom view thereof;

FIG. 7 is a left side view thereof; and,

FIG. 8 is a top plan view thereof.

The broken lines are shown for environmental purposes only and form no part of the claimed design.

1 Claim, 8 Drawing Sheets
